UNITED STATES PATENT OFFICE.

LODONZO C. ENGLE, OF KELLER, WEST VIRGINIA.

RAILWAY-TIE AND FASTENING.

1,001,938.

Specification of Letters Patent. Patented Aug. 29, 1911.

Application filed April 24, 1911. Serial No. 622,991.

To all whom it may concern:

Be it known that I, LODONZO C. ENGLE, a citizen of the United States, residing at Keller, in the county of Jefferson and State of West Virginia, have invented certain new and useful Improvements in Railway-Ties and Fasteners, of which the following is a specification.

My invention relates to railway ties adapted for steam, electric or other railways and means for securing the rails to the ties.

My invention has for its object to provide a tie which is adapted to be constructed of metal which will be comparatively inexpensive to construct and will be practically indestructible.

A further object of the invention is to provide fastening means for securing rails to ties which may be readily put in place and will hold the rail firmly in place without liability to creeping.

A further object of the invention is to provide a tie and fastening means adapted to permit adjustment of gage.

With these and other objects hereinafter explained in view, my invention consists in the construction and combination of elements hereinafter described and particularly pointed out in the claims.

Referring to the drawings—Figure 1 is a side elevation showing one end of a tie having my improved fastening means applied thereto, Fig. 2 is an end view of the tie and fastening means shown in Fig. 1, Fig. 3 is a perspective view of one of the securing hooks with the cross connecting means, Fig. 4 is a plan view of the plate on which the rail rests on the rail supporting member, Fig. 5 is a side elevation of a modified form of base member, Fig. 6 is an end view of the modified form shown in Fig. 5, and Fig. 7 is a perspective view of the inverted U-shaped portion of the base member shown in Figs. 5 and 6.

In the drawings 1 is a rail supporting member or base member, here shown as consisting of a pair of inverted T beams arranged side by side and preferably having their flanges turned up slightly at their outer edges to facilitate tamping, as shown at 2. The upwardly extending webs 3 of these T beams are suitably apertured to receive bolts 4 and 5 which are parallel, and each extend through the legs 3 of both T beams.

Upon the upper edges of the webs 3 of the T beams rests a plate 7 notched at oppo-

site sides, as shown at 8. The plate 7 of each supporting member 1 extends to and abuts at its ends against the end of the plate 7 of the next base member, thus spacing the base members apart and being thus held against creeping. The notches 8 are immediately above the bolts 4 and 5 when the device is assembled. On the plate 7 is a strip of non-metallic, resilient material, such as rubberoid or wood fiber, 11, upon which the rail 12 rests. This strip of rubberoid or wood fiber gives some resiliency, deadens noise, and may also be made use of as a part of means for insulating the rails. The plate 7 is provided with apertures 9, through which pins 10 extend into engagement with the inner sides of the webs 3 of the T beams of the base members, thus preventing movement of the plate relative to the rail supporting member.

The rail 12 is secured to the base member by hooks 13, one of which is carried by each of the two bolts 4 and 5. These hooks have their upper ends bent inward, as shown at 15, the lower faces of these ends being serrated, as shown at 16, and are adapted to fit over and engage the flanges of the rail. The hooks have their lower ends formed with open loops 14, so as to be readily engaged with and disengaged from the bolts 4 and 5. Near the ends 15 the hooks 13 are formed with an offset 17, having an opening therein to receive the end of a rod 18, the other end of which is provided with a hook 19 to engage the bolt 4 or 5 opposite that which carries the hook 13, to which the rod 18 is secured.

The outer end of the rod 18 is screw threaded to receive a nut 20. In order to secure the rail in position, the hooks 13 are engaged with the bolts 4 and 5 and their upper ends are swung into the notches 8 of the plate 7, and their serrated faces 16 are caused to engage the opposite flanges of the rail. The rods 18 are then placed in position and the nuts 20 screwed upon their ends. This forces the upper ends of the hooks inward, causing them to clamp the rail firmly in place. Suitable lock nuts will of course be used to prevent nuts 20 from becoming loose.

In Figs. 5, 6 and 7 I have shown a modified form of the invention, in which an inverted U-shaped bar 21 rests upon the upper edges of the webs 3 of the T beams. The flanges of this inverted U-shaped bar extend

down below the plane of the bolts 4 and 5, and are provided with slots 22 and 23 to receive these bolts. These flanges rest against the outer faces of the webs 3 of the 5 T beams, and the bolts 4 and 5 unite the inverted U-shaped bar and the T beams into a complete railway tie. Two inverted U-shaped bars are employed with each tie, these bars being each only slightly longer 10 than the width of the bottom of the rail. The ends of these bars are preferably notched, as shown at 24, to receive the hooks 13.

By reason of the fact that the plates 7 15 abut one against another, they form a practically continuous bed for the rail.

By screwing up the nut 20 on one of the rods 18 and unscrewing the corresponding nut on the other rod, the rail may be moved 20 in or out, as may be found necessary to adjust its position to gage. In thus moving the rail in or out the inverted U-shaped bar moves with the rail, the slots 22 and 23 permitting this movement, while the bolts 4 25 and 5 remain permanently in position.

The fastening means also permits the rails to be leveled up to some extent by adjusting the nuts 20, though if substantial 30 change in level is necessary, hooks 13, of greater or less length, may be substituted for those in use before leveling up.

It will of course be understood that I do not desire to be limited to the use of particular materials for any of the parts of 35 the devices above described, nor do I wish to be limited to details of construction and arrangement, it being obvious that many changes in the form and details of construction may be made without departing from 40 the spirit of the invention.

Having thus described my invention, what I claim is:

1. In a railway tie a base supporting member, a pair of bolts extending through the 45 base member, a hook carried by each bolt having its upper ends adapted to engage the flange of a rail and connections between each hook and the bolt which carries the other hook.

50 2. In a railway tie a base member, a plate between the base member and the rail having notches formed in its opposite sides, a pair of bolts extending through the base member, a hook carried by each bolt extending 55 through a notch of said plate and having its upper ends adapted to engage a

flange of the rail, and means for holding the hooks against the rail.

3. In a railway tie a base member, a pair of parallel bolts extending through the base 60 member, a hook carried by each bolt having its upper end inwardly bent and serrated on its under side adapted to engage the flange of a rail and adjustable connections between each hook and the bolt which carries the 65 other hook.

4. In a railway tie, a base member having parallel upwardly extending webs, bolts extending through the webs, a plate resting on the upper edges of the webs, a resilient non-metallic strip resting on the plate, a rail resting on the non-metallic strip, hooks carried by the bolts engaging the rail and plate, and means for clamping the hooks against 70 the flange of the rail. 75

5. In a railway tie, a base member having parallel upwardly extending webs, bolts passing through the webs, a plate resting on the upper edges of the webs having notches in its opposite edges, pins extending through 80 the plate into engagement with the webs, hooks carried by the bolts, each having its upper end adapted to extend through a notch in the plate and to engage the flange of the rail, and means for clamping the 85 hooks against the flange of the rail.

6. In a railway tie, a rail supporting member, an inverted U-shaped bar resting on the rail supporting member with its flanges extending downward, a pair of bolts 90 extending through the supporting member and the flanges of the inverted U-shaped bar, a hook carried by each bolt, having its upper end adapted to engage the flange of a rail, and adjustable connections between 95 each hook and the other bolt of the pair.

7. In a railway tie, a base member, an inverted U-shaped bar resting on the base member with its flanges extending downward and provided with slots, a pair of 100 bolts extending through the base member and through the slots of the inverted U-shaped bar, hooks carried by each of the bolts, having their upper ends adapted to engage the flange of a rail and adjustable 105 connections between each hook and the other bolt of the pair.
